PERMANENT WAVING

Hobart N. Durham, Munsey Park, N. Y.

Application November 7, 1933, Serial No. 696,979

9 Claims. (Cl. 132—33)

The invention relates to a novel and improved apparatus for curling or winding hair and more particularly to a novel and improved power-driven apparatus for winding curls on the human head in the process of permanent waving.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction, arrangements, combinations and improvements herein shown and described.

The accompanying drawings, referred to herein and constituting a part hereof, illustrate one embodiment of the invention, and together with the description, serve to explain the principles 20 of the invention.

Of the drawings:—

Figure 1 is a side elevation of an illustrative embodiment of the present invention, certain parts being broken away;

Figure 2 is a detail vertical section of the driving connection between the motor and the reduction gearing;

Figure 3 is a detail sectional view taken on the line 3—3 of Figure 2;

Figure 4 is a detail, fragmentary side elevation of an illustrative form of the curl-winding device of the present invention, the handle portion being shown in section; and

Figure 5, 6 and 7 are sectional views taken on the lines 5—5, 6—6 and 7—7 respectively of Figure 4.

The present invention has for its object the provision of a new and improved power-driven curl-winding device particularly adapted for use in the permanent waving of hair. Another object is the provision of such a curl-winding device having improved power-control means for controlling the operation thereof.

In certain respects, the present invention is an improvement upon the power-driven curl-winding device shown and described in the pending application of Virginio J. Gentile Ser. No. 676,459, filed May 11, 1933, but in other respects the invention is of more general application.

In accordance with the present embodiment of the invention, means are provided for tensioning and winding a growing tress of human hair helically about a curling rod, and preferably for covering the tress with tape as it is wound. Motor 55 means are provided for rotatably driving the winding head about the curling rod, and preferably comprise an electric motor coupled to the winder by means of a flexible shaft, reduction gearing and a friction or centrifugal clutch. In 60 accordance with the present invention, the driv-

ing motor is controlled by means of a switch in the motor circuit and positioned in the hand-grip portion of the winder where it is always easily accessible to the operator and can be readily manipulated so as to insure perfect control at all times of the winding operation.

It will be understood that the foregoing general description and the following detailed description as well, are exemplary and explanatory of the invention but are not restrictive thereof.

Referring now in detail to the illustrative embodiment of the invention as shown in the accompanying drawings, the winding means comprises a handle portion 10 in which is rotatably mounted a relatively long tubular body 11 adapted to receive an axially movable curling rod on which the hair is to be wound. At the forward end of the tubular body 11 is positioned a comb and tensioning means 12 through which the hair passes as it is wound on the curling rod, and tape guiding means 13 for guiding tape and wrapping it around the wound hair during the winding operation. A shaft 15 projects from the tubular body 11 and is adapted to support a roll of tape 14. Inasmuch as the details of the foregoing construction comprise no part of the present invention, they will not be further shown or described.

The rear portion of the cylindrical body 11 is preferably provided with an internal gear 16 adapted to mesh with a driving pinion 17 rotatably mounted in the handle portion 10 by means of an integral shaft 18, which in turn is driven from the keyed end 19 of flexible shaft 20 detachably secured to the rear of the hand grip 10, as shown in detail in Figure 4 of the drawings.

The weight of the winding head and flexible shaft is preferably supported by means of a cord 21 running over pulleys 22 which are rotatably mounted in the horizontal arm 23 extending laterally from the standard 24, the other end of the cord 21 being connected to a counterweight 25 which balances the weight of the winder and shaft and is adapted to hold the winding head 105 in any vertical position.

Within the base 26 from which rises standard 24, is located the driving motor 27 which is adapted to transmit power through a suitable friction clutch through the reduction gearing 28 and thereby drive the vertical shaft 29 which is operatively connected with the lower end of the flexible shaft 20. The friction clutch limits the amount of power which can be transmitted by the motor to the winder, and thereby prevents 110 stalling of the motor in case a snarled tress of hair prevents rotation of the winder head. However, I prefer to use a centrifugally operated friction clutch so as to insure smooth and relatively slow starting of the winder, and for this pur- 120

pose the motor shaft 30 is provided at one end with a centrifugal clutch spider 31 received within the centrifugal clutch drum 32 and coaxial therewith, drum 32 being rigidly secured to the 5 end of the high speed shaft 33 of reduction gearing 28. The radial vanes of clutch spider 31 drive the weighted friction blocks 34, and when the motor has attained sufficient speed, these blocks 34 are forced radially outward into engagement with the inner cylindrical surface of 10 the drum 32, causing it to be rotated. In case the load on the winder is too great, the spider 31 and blocks 34 rotate within the drum 32, but under normal conditions they rotate with the 15 drum until the motor is stopped thereby releasing the pressure of the blocks against the drum.

For controlling the application of power to the motor and thereby the rotation of the winder, the interior of the hand gripped portion 10 of the 20 winder head is preferably recessed and receives the spring mounted contacts 38 which are supported on a block of insulated material 39, and are connected in series with the motor by means of conductors 40. For conveniently operating the 25 switch during the use of the winder, a small bell crank 42 is pivotally mounted in the hand grip 10 by means of pivot pin 43 supported on brackets 44 mounted on hand grip 10, the longer portion of the bell crank projecting forwardly of 30 the winder, and its short arm being adapted to bear against and move the insulated head 45 of spring plunger 46.

As the operator presses down on the forward 35 end of bell crank 42, the switch contacts 38 are closed thereby causing power to be supplied to motor 27 from the conductor 50 and to conductors 40. As soon as the curl has been completely 40 wound, or whenever the operator desires to stop the winding operation for any reason, he need only remove his finger from the bell crank lever 42 to stop the motor, the contacts being open by virtue of their own resiliency, and lever 42 being 45 raised to the position shown in Figure 4 by means of the spring plunger 46.

The invention in its broader aspects is not 50 limited to the specific mechanisms shown and described but departures may be made therefrom within the scope of the accompanying claims without departing from the principles of the invention and without sacrificing its chief advantages.

What I claim is:—

1. In a curl winding device, the combination of 55 a hand grip by which a curling rod may be supported, means rotatable with respect to said rod for tensioning and winding a tress of hair on said rod, motor means for rotating said rotatable means and a lever carried by said hand grip for controlling the supply of power to said motor 60 means.

2. In a curl winding device, the combination of 65 a hand grip by which a curling rod may be supported, means rotatable with respect to said rod for tensioning and winding a tress of hair on said rod, a base, a support on said base and on which said hand grip and rotatable means are supported, an electric motor in the base operatively connected to rotate said rotatable means, a switch and an operating lever therefor carried by said hand grip, said switch being connected to the motor to control power supplied thereto.

3. In a curl winding device, the combination of 70 a hand grip by which a curling rod may be supported, means rotatable with respect to said rod for tensioning and winding a tress of hair on said

rod, a base, a support on said base and on which said hand grip and rotatable means are supported, an electric motor in the base operatively connected to rotate said rotatable means through a friction clutch, a switch and an operating lever therefor carried by said hand grip, said switch being connected to the motor to control power supplied thereto. 80

4. In a curl winding device, the combination of 85 a hand grip by which a curling rod may be supported, means rotatable with respect to said rod for tensioning and winding a tress of hair on said rod, a base, a support on said base and on which said hand grip and rotatable means are supported, an electric motor in the base operatively connected to rotate said rotatable means through a centrifugal clutch, a switch and an operating lever therefor carried by said hand grip, said switch being connected to the motor to control power supplied thereto. 90

5. In a curl winding device, the combination of 95 a hand grip by which a curling rod may be supported, means rotatable with respect to said rod for tensioning and winding a tress of hair on said rod, motor means for rotating said rotatable means and connected thereto through a friction coupling and a lever carried by said hand grip for controlling the supply of power to said motor means.

6. In a curl winding device, the combination of 100 a hand grip by which a curling rod may be supported, means rotatable with respect to said rod for tensioning and winding a tress of hair on said rod, motor means for rotating said rotatable means and connected thereto through a centrifugal clutch and a lever carried by said hand grip for controlling the supply of power to said motor means. 105

7. In a curl winding device, the combination of 110 means for supporting a curling rod, means rotatable with respect to said rod for tensioning and winding a tress of hair on said rod, motor means for rotating said rotatable means, a friction clutch through which the motor is connected to drive said rotatable means and means for starting and 115 stopping the application of power to said rotatable means.

8. In a curl winding device, the combination of 120 means for supporting a curling rod, means rotatable with respect to said rod for tensioning and 125 winding a tress of hair on said rod, a hand grip in which said rotatable means is mounted for rotation, motor means for rotating said rotatable means, a friction clutch through which the motor is connected to drive said rotatable means and 130 means carried by said hand grip for starting and stopping the application of power to said rotatable means, the means carried by said hand grip being easily accessible to the operator while the grip is held in the operator's hand. 135

9. In a curl winding device, the combination of 140 means for supporting a curling rod, means rotatable with respect to said rod for tensioning and winding a tress of hair on said rod, a hand grip in which said rotatable means is mounted for rotation, motor means for rotating said rotatable means, a friction clutch through which the motor is connected to drive said rotatable means, a lever carried by said hand grip for starting and stopping the application of power to said rotatable 145 means, and spring means for normally positioning said lever to stop the driving of said rotatable means.

HOBART N. DURHAM.
